CHARLES A. ROBINSON, OF WASHINGTON, DISTRICT OF COLUMBIA, ASSIGNOR TO
WESTERN ELECTRIC COMPANY, INCORPORATED, OF NEW YORK, N. Y., A CORPORATION OF NEW YORK.

SIGNALING SYSTEM.

Application filed December 17, 1921. Serial No. 523,013.

To all whom it may concern:

Be it known that I, CHARLES A. ROBINSON, a citizen of the United States, residing at Washington, in the District of Columbia, have invented certain new and useful Improvements in Signaling Systems, of which the following is a full, clear, concise, and exact description.

This invention relates to signaling systems in which it is desired to transmit currents of different frequencies at different times as, for instance, the talking and ringing frequencies in a telephone circuit. The object of the invention is to make the circuit efficient for transmitting currents of either frequency range.

Transmitting circuits containing transformers or other localized inductance are usually designed to transmit most efficiently the particular range of frequencies which it is expected to employ, and a circuit so designed is relatively inefficient for transmitting other frequencies. One case in which this inefficiency becomes a serious difficulty is in connection with repeaters such as vacuum tube repeaters used in a telephone transmission line. The transformers or inductances used throughout the circuit and particularly in the immediate input and output circuits of the repeater are such as to transmit telephone frequencies with good efficiency but ringing currents are so discriminated against that in spite of amplification by the repeater they may not be able to operate the ringers at the terminal of the line. This difficulty has been overcome in part by changing the character of the input circuit during ringing, as for example, by making the input circuit resonant for ringing frequency. This may be accomplished by suitably operated relays as will be described later, these relays being operated by the output ringing current. I find however that in some cases this amplified ringing current is not large enough to operate the relays with certainty. My invention resides in further increasing the efficiency and certainty for ringing frequencies and in brief, consists in increasing the gain of the repeater, thereby increasing the output of ringing current to a value which will operate the relay with certainty. This, however, will also increase the gain for the telephone currents and raise it to a

transmission level in excess of that intended for that portion of the line. Accordingly in my invention I provide means to attenuate the output of the repeater in a manner which does not affect the operation of the relays.

The invention will be better understood by reference to the accompanying drawings, in which Fig. 1 shows a circuit embodying my invention. Fig. 2 is a modification thereof, showing certain disposition of impedance elements to obtain the desired results. Figs. 3, 5 and 7, show specific arrangements for obtaining the desired results, and Figs. 4 and 6 are curves illustrating the operation for the circuits of Figs. 3 and 5.

In Fig. 1, 11 represents an incoming transmission line over which may be transmitted both telephone currents and ringing currents. A vacuum tube repeater element 12 has its input associated with the line 11 by means of a transformer 14, its output being associated with the outgoing line 15 by means of the transformer 16. The strength of the input impulses impressed on the repeater element may be controlled by a potentiometer 17 in a well-known manner. Power for the repeater element is supplied by a battery 18 connected from filament to plate and including in its circuit a retard coil 19. The very low efficiency of the circuit for ringing frequencies, due to the design of the transformers 14 and 16, has in part been overcome by the introduction of a relay 20 through which the alternating current component of the output of the amplifier of ringing frequency may pass. The condensers 21 and 22 are inserted as shown to prevent the discharge of the battery 18 through the output of the repeater element and to offer a path of low impedance for high frequencies around the relay 20. The relay 20 through its contact 23 controls a second relay 24. Through its front contact the relay 24, which is normally actuated, connects the potentiometer 17 across the primary of the transformer 14. Through its back contact this relay upon release, bridges a condenser 27 across the primary of the transformer 14 and the potentiometer 17 is cut out by the opening of the front contact. The capacity of the condenser 27 is so chosen that with the primary of the

transformer 14, it constitutes a circuit anti-resonant at the ringing frequency and thus substantially increases the efficiency of the repeater as a whole for ringing frequencies.

5 The circuit as thus far described is substantially that now commonly used in practice, but it is found that in the case of repeaters working at a low energy level there is considerable uncertainty as to the operation 10 of the relay 20 for the reason that the ringing current in the output of the repeater may be too small. To increase the certainty of operations, I increase the gain of the repeater by adjusting the potentiometer 17 15 to such a point that the amplified ringing current can be relied on to operate relay 20 without fail. It is desirable, however, that the telephone current transmitted over the line 15 shall have a certain amplitude and 20 the gain due to the new adjustment of the potentiometer should be compensated in some manner. This latter, I accomplish by 25 means of a network Z , which will act as a substantial shunt or attenuating device for the primary of output transformer 16, so far as telephone frequencies are concerned. It may also act as a shunt or attenuating device for the ringing current but in any case 30 it can be made of such a character that it does not appreciably affect the ringing current flowing through relay 20; on the other hand the shunt may be of a character which will not shunt the ringing current but cause 35 it to follow its former path through the primary winding.

Referring more specifically to the network Z , it is apparent that it may take on a large variety of forms. It may, for example, consist of a simple shunt selective for 40 higher frequencies. In Fig. 2, I have shown it as consisting of the impedance elements Z_1 , Z_2 and Z_3 , arranged in a T-formation, which is adapted for a wide latitude of adjustment in regard to impedance characteristics. This latter is desirable for the reason 45 that the introduction of a simple shunt such as Z_3 across the output circuit would not only shunt off a part of the telephone current, but would at the same time change the apparent impedance of the output circuit 50 as viewed from the repeater element. The introduction of the additional elements Z_1 and Z_2 makes it possible to shunt off whatever portion is desired of the telephone currents, and at the same time to maintain unchanged the impedance of the circuit 55 whether viewed from the repeater element looking towards the output line, or viewed from the output line looking towards the repeater element. In this Fig. 2 I have, for 60 the purpose of illustration, also shown a modification in the input circuit. Here again the relays 20 and 24 are connected and operated in the same manner as for Fig. 1. 65 The front contact of the relay 24 also oper-

ates in the same manner. However, there is shunted around the front contact, resistance element 28 so that the condenser 27 at all times is bridged around the primary of the transformer 14. However, during the 70 transmission of voice currents there is, in series with this condenser 27, the resistance 28, but upon the transmission of ringing current the resistance 28 is short-circuited and the condenser 27 with the primary of the transformer is highly anti-resonant for the ringing frequency. During speech transmission the presence of the condenser 27 alone would render the circuit highly inefficient for voice currents but the presence 80 of the resistance 28, which is given a suitable value, will maintain a reasonable efficiency for speech currents which at the same time will be less than that given by the circuit of Fig. 1. Thus a further discrimination 85 is given in favor of the ringing current.

Referring to the network introduced in the output circuit, one specific form which it may have is shown in Fig. 3, in which Z_1 and Z_2 are resistance elements, and Z_3 is a series resistance and capacity shunted across the line. By suitable adjustments of these elements it is possible to obtain attenuation without change of the impedance of the circuit, viewed in either direction. Fig. 4 95 shows the amplification characteristic of such a circuit as that of Fig. 3. Curve a gives the amplification characteristic for the normal circuit without the network and the introduction of the network is such as to 100 reduce the amplification to the dotted curve b . The presence of the anti-resonant circuit in the input circuit, however, alters this substantially at the ringing frequency so that the curve takes on the modified form indicated by the full line hump on the curve b . The amplitude of the telephone current may 105 now be restored to substantially its former value by means of the potentiometer 17 and the resulting amplification characteristic is 110 given by curve c . In some cases it may be desirable to remove the condenser from the impedance Z_3 , which will obviously alter the characteristic, for in this case the attenuation 115 will not be selective with respect to frequency.

Another form which the network may take on is shown in Fig. 5. It consists of a wave filter of the low pass type now well known in the art, and consisting of series inductances and shunt capacities. In order to prevent too complete filtering out or attenuation of the telephone currents it may be desirable to introduce resistances R in series with the condensers. The amplification characteristic for such a circuit is shown in Fig. 6. Curve a represents the normal amplification characteristic for the circuit without the network, and the dotted curve b gives the new characteristic result- 125 130

ing from the introduction of the network of Fig. 5. The selective nature of the impedance in question is such that the curve *b* shows a slight hump at the ringing frequency. However, when the relays 20 and 24 have been operated the efficiency for ringing currents has been increased, as indicated by the full line hump on the curve *b*. Upon restoring the telephone current to its 10 normal value by means of the potentiometer 17 there is obtained the characteristic given by curve *c*, and thus it is possible to obtain at the terminal station ringing current of sufficient strength to operate the ringing 15 apparatus.

Thus far I have described these networks as being introduced directly and conductively in the output circuit of the repeater element. It should be understood, however, 20 that the network may be introduced in other parts of the circuit. In Fig. 7, for example, I have shown the network *Z* in the secondary of the transformer 16 instead of the primary, the dotted portions of the line indicating that it may be introduced at any 25 desirable place in said line 15. In this Fig. 7, I have shown the relay mechanism of Figs. 1 and 2 conventionally only at 29, it being understood that this relay circuit may 30 be either that of Fig. 1 or Fig. 2, or any such obvious modifications as might occur to those skilled in the art.

While I have described certain specific networks in Figs. 2, 3 and 5, it is to be 35 understood that these are shown for illustrative purposes only and that other forms of networks may be used.

What is claimed is:

1. In combination, a repeater circuit 40 adapted to amplify voice frequency currents with high efficiency and ringing current with relatively low efficiency and having an input and an output circuit therefor, means operative on the input circuit for increasing 45 the efficiency of said repeater for ringing current, and an impedance in the output circuit for further increasing the relative efficiency of amplification of the ringing current compared to the voice frequency 50 current.

2. In a repeater circuit adapted to amplify voice frequency with high efficiency and ringing current with relatively low efficiency, an input and an output circuit there- 55 for, means operative on the input circuit and by the ringing current in the output circuit for increasing the efficiency of said repeater for ringing current, and an impedance in the output circuit for further in- 60 creasing the relative efficiency of amplifi-

cation of the ringing current compared to the voice frequency current.

3. In a repeater circuit adapted to amplify voice frequency with high efficiency and ringing current with relatively low efficiency, an input and an output circuit there- 70 for, a relay controlled by the output ringing current and adapted on operation to render the repeater efficient for ringing current, means in the output circuit for producing a substantial attenuation of 75 the voice frequency currents while producing a negligible attenuation of the ringing current, and means in the input circuit for increasing the gain of the repeater.

4. In a telephone repeater circuit, the 80 method of increasing the relative efficiency of amplification of a repeater element for ringing currents which consists in shunting off part of the talking current in the output circuit while maintaining sub- 85 substantially constant the apparent impedance of the output circuit as viewed from said element.

5. In a telephone repeater circuit, the 90 method of increasing the efficiency of amplification of a repeater element for ringing currents which consists in shunting off part 95 of the talking current in the output circuit while maintaining substantially constant the apparent impedance of the output circuit as viewed from said element, and in increasing the repeater gain.

6. In a repeater circuit adapted to amplify voice frequency with high efficiency and ringing current with relatively low efficiency, an amplifying repeater having input and output terminals, an input circuit comprising said input terminals, an output circuit comprising said output terminals, an incoming line coupled to said input circuit, 100 an outgoing line coupled to said output circuit, means operative on the input circuit for increasing the efficiency of said repeater for ringing current, and a network in said output circuit for producing a substantial 105 attenuation of the voice frequency current while producing a negligible attenuation of the ringing current, said network being arranged such that the impedance of said outgoing line, as seen from said output terminals, is substantially unchanged by the 110 presence of said network.

In witness whereof, I hereunto subscribe my name this 15th day of December A. D., 1921.

CHARLES A. ROBINSON.

Witness:

WILLIAM A. KEMPER.
